CARTON

Bruce J. Davidson, Kew Gardens, N. Y., assignor
to National Biscuit Company, New York, N. Y.,
a corporation of New Jersey

Application March 17, 1932, Serial No. 599,375

2 Claims. (Cl. 229—51)

My invention pertains to cartons, and particularly to cartons adopted for the packaging of biscuits, crackers, and other food products.

Cartons of this type, as heretofore used, have 5 consisted generally of an outer carton or box formed from a cardboard blank and a liner formed from a sheet of waxed paper, and the present invention has for its principal object to improve cartons of this kind.

10 Another object of the invention is to decrease the cost of cartons by reducing the amount of material used and at the same time produce a carton that is easily assembled and that can be formed and filled by existing machinery.

15 Other objects are to produce a carton in which the liner will be securely held in the box so as to prevent its displacement either when the box is being filled or after it has been opened and its contents are being used.

20 Still other objects are to produce a carton that can be filled through its widest side and reopened at the end or at the side, as may be desired, and reclosed after part of its contents have been removed.

25 The above and other objects and advantages will be apparent from the following description of the invention, having reference to the accompanying drawings, illustrating one embodiment thereof wherein

30 Fig. 1 is a plan view of the blank and liner from which the carton is formed.

Fig. 2 shows the blank and liner partly formed, the end flaps of the carton having been turned in so as to engage the lower folds of the liner.

35 Fig. 3 shows the carton ready to receive the end panels.

Fig. 4 shows the carton and liner ready to be filled.

Fig. 5 shows the carton filled, and ready for 40 the final closing operation.

Fig. 6 shows the carton filled and sealed.

Fig. 7 shows the carton opened on one side.

Fig. 8 shows the carton opened at one end.

As shown in Fig. 1, one form of my invention 45 comprises a carton blank indicated generally by the number 10 and the liner by 11, the latter being a rectangular piece of moisture-proof paper, or other suitable material, of the proper dimensions, somewhat larger in area than the carton blank; and lying on top of it in this figure.

The blank 10 is cut and scored to provide a bottom 12, sides 13, 14, and a top 15, the top having a tuck 16 at one side. The bottom has 50 a flap 17, 18 at each end, and the two sides have

end flaps 19, 20, 21, 22, all of said flaps 17 to 22 preferably being of the same width and very narrow so as to economize in material, usually only wide enough to provide sufficient gluing surface and support for the end panels. The 5 blank may also have one or more tear-lines 31, 35 along which the box may be torn to open it or the box may be sealed and opened in any desired manner.

The ends of the box preferably are formed 10 from separate pieces 23, 24, which, when the box is assembled, are glued to the end flaps 17, 20, and 22, and 18, 19, and 21, respectively. These end flaps also have tucks 25, 26 which are turned in over the top of the box when it is filled as 15 best shown in Figs. 5 and 7.

When the box is to be formed, the blank 10 is fed to the forming machine with the line 11 lying on top of it. The sides 13 and 14 are then folded up along the score lines, carrying parts 20 of the liner with them. The next operation is to fold the ends of the liner and the rear flaps 21, 22, inwardly, and then the front part of the liner and the end flaps 19, 20, are folded rearwardly so that the parts assume the position 25 shown in Fig. 2. In that position it will be noted that the end of the liner has been folded to form a triangular-shaped fold 27 and that the flaps 20, 22 are turned in with their lower edges in engagement with this triangular fold, and 30 that the ends of the liner have only a slight overlap as shown at 27'.

It will also be noted that this fold 27 lies on top of the flap 17. The next operation is to fold the flaps 17 and 18 into vertical position, which 35 carries the triangular folds 27 with them, the triangular folds now being partly outside of the flaps 20, 22 at one end, and at the other end of the box, outside of the flaps 19, 21. It will thus be seen that the flaps 20, 22 at one end 40 of the box and the flaps 19, 21 at the other end of the box lock the liner in position so that it cannot be removed.

The next operation is to apply glue to the flaps at the ends of the box as indicated at 45 28, 30 on Fig. 3. The glue is applied in this manner to the flaps at both ends of the box, and then the end pieces 23, 24 are set on by the box forming machine. The glue, applied to the flaps 29, 30 at one end, is preferably put on in 50 dots or spots so that the end 23 will not adhere too tightly to these flaps, but the seal can be broken. This is done so that if the box is provided with the tear-line 31, the carton can be opened at this end and this will be done by

breaking the tear-line 31, as indicated in Fig. 8, and then turning back the end panel by pulling it loose from the flaps 20, 22. The flaps 20, 22 can then be turned up, and access had to the 5 contents of the box through this end.

The box can be reclosed by again inserting the tuck 25 within the front panel 15.

Fig. 4 shows the carton after it has been 10 fully formed and has passed on to the filling machine to be filled. It will be noted that the carton is open on its widest face and can be 15 readily filled. Fig. 5 shows the carton after it has been filled, and with the liner front and end tucks folded down. Glue has been applied 20 to the cover and tuck 16, as indicated by the numbers 32, 33, and 34, the glue 34 being applied on the outside of the tuck 16 so that it will 25 adhere to the front panel 14 above the tear-line 35. Fig. 6 shows the carton in its final, assembled position after it has been filled.

The carton may be opened either at the end 25 or at the side or at both an end and side, and without any change in the shape of the blanks 30 or machinery to make the cartons, and Fig. 8 shows the carton opened at the end, as previously described. If it is desired to open the carton at the side, it will be broken along the tear-line 35, as shown in Fig. 7, and the cover raised 35 up, the glued spots 32, 33 being only strong enough to keep the carton sealed, and not of sufficient strength to prevent the cover from being readily opened.

While I have shown and described a liner used 35 in connection with my improved carton, it is to be understood that the carton may be used either with or without a liner, as may be required under different conditions and with different materials. It is also to be understood 40 that the terms which I have used in describing my improved carton, such as "ends, top, bottom, sides," etc., are used only in a descriptive sense to identify different parts of the box, and are not to be considered as limitations. For example, the wall that may be called an "end" 45 in Fig. 4 becomes a top or lid in Fig. 8, and the front and rear walls in Fig. 7 become end walls when the carton is turned to the position shown in Fig. 8.

I have shown the ends 23, 24 as separate 50 pieces, but that is not necessary in this inven-

tion because the bottom flaps 17, 18 in some instances are made long enough to form the ends of the box and tucks 25, 26. When the end pieces are separate, less material is usually required in making the carton.

In cases where it is desired to open the carton only at one end as shown in Fig. 8, the tear-line 35 and the tuck 16 may be omitted and the front panel 14 provided with a tuck similar to the tucks 25, 26. The top 15 will then be tightly 10 glued to the tucks on the side and one end, but will be glued to the tuck 25 only within the tear-line 31.

Having thus described my invention, what I claim and desire to secure by Letters Patent is 15 defined in the following claims and all equivalents thereof:

1. A lined carton formed from a blank and liner folded together, the blank having side and bottom panels with narrow flaps at the ends of each side and the bottom, the liner and sides of the blank being folded upwardly and the ends of the liner turned inwardly to form an outwardly extending bottom fold at each end, the side flaps being turned inwardly to engage over said 20 folds, and the end folds and bottom flaps being turned upwardly outside of said end flaps, and separate end panels secured to the outside of 25 said side and bottom flaps.

2. A lined carton formed from a blank and liner folded together, the blank having side and bottom panels with narrow flaps at the ends of each side, the liner and sides of the blank being folded upwardly and the ends of the liner turned inwardly to form a narrow overlap near 35 the center and an outwardly extending bottom fold at each end with the end flaps turned inwardly over said bottom folds, said end flap being less than one half the width of the bottom panel, said folds being turned upwardly outside of said flaps, and separate ends overlying and secured to said flaps to secure the liner within the carton, said ends having tucks extending inwardly over said liner, and a top 40 secured to one side of the carton and having a tuck inserted between the opposite side and liner, said tucks adjacent their attached edges 45 being secured to the overlying side and top of the carton.

BRUCE J. DAVIDSON.
